OTHER PUBLICATIONS

Pattern Design Publication, 1963, p. 226, Pattern No. 259, Wave Pattern.

The single FIGURE is a front perspective view of a tear strip carton showing my new design.

Primary Examiner—Bernard Ansher

Assistant Examiner—Prabhakar Deshmukh

[57] **CLAIM**

The ornamental design for a tear strip carton, as shown and described.

DESCRIPTION

FIG. 1 is a perspective view of a bottle showing my new design;

FIG. 2 is a top plan view thereof drawn to a scale enlarged from that of FIG. 1;

FIG. 3 is a side elevational view thereof, the opposite side being the same in appearance;

FIG. 4 is a front elevational view thereof, the rear elevational view being the same in appearance; and

FIG. 5 is a bottom plan view thereof.

U.S. Patent

Sep. 25, 1990

D310,784

UNITED STATES PATENT AND TRADEMARK OFFICE
CERTIFICATE OF CORRECTION

PATENT NO. : DES. 310,784

DATED : September 25, 1990

INVENTOR(S) : Hampton E. Forbes, Jr.

It is certified that error appears in the above-identified patent and that said Letters Patent is hereby corrected as shown below:

On title page, under heading OTHER PUBLICATIONS, please cancel
"The single FIGURE is a front perspective view of a tear
strip carton showing my new design."

On title page, under heading DESCRIPTION, please cancel beginning,
"FIG. 1 is a perspective view of a bottle showing my new design;"
to and including, "FIG. 5 is a bottom plan view thereof.", and
substitute therefor:

--The single FIGURE is a front perspective view of a tear
strip carton showing my new design.--

Signed and Sealed this

Sixteenth Day of February, 1993
